UNITED STATES PATENT OFFICE.

WILLIAM CLARENCE RAND, OF LEWISTON, MAINE.

GASOLENE-BURNER.

SPECIFICATION forming part of Letters Patent No. 690,608, dated January 7, 1902.

Application filed June 18, 1900. Serial No. 20,650. (No model.)

To all whom it may concern:

Be it known that I, WILLIAM CLARENCE RAND, a citizen of the United States, residing at Lewiston, in the county of Androscoggin and State of Maine, have invented a new and Improved Gasolene-Burner, of which the following is a specification.

My invention relates to heating-burners which employ gasolene or other easily-vaporized liquid as fuel, and is especially designed for vehicles propelled by steam, and certain characteristic features hereinafter set forth peculiarly adapt it to this use. For this purpose it is desirable that the upward current of heated air and gas in each boiler-tube should be as nearly as possible the same both in quantity and temperature as in every other and that this upward current should be capable of supplying each tube upon occasion with all the heat it can safely transmit to the water and steam. Furthermore, it is of course desirable that no hydrocarbon vapor shall pass through the boiler tubes without being consumed and that the supply of air for feeding and diluting the flame shall at all times adjust itself to the amount of vapor supplied.

The requirements above mentioned become very difficult to meet in the construction of a burner which is to be used on a moving vehicle on account of the air-currents, which are liable to shift suddenly both in strength and direction.

A part of the above difficulties are avoided in devices now in use. Their construction, however, does not provide for the very intimate mixture of air and vapor which is desirable before burning, and the upward draft through the air-tubes cannot mix thoroughly with the contents of the burning-chamber before entering the boiler-tubes.

A principal object of my invention is to provide a burner which shall meet the requirements above mentioned and shall also insure the thorough mixture of the air and vapor before burning and a uniform dilution with air of the intensely-heated products of combustion before they enter the boiler-tubes.

A further object of my invention is to provide a burner which shall be durable in use and easy to repair and replace.

In the accompanying drawings, Figure 1 is

a plan of my device; Fig. 2, a partial sectional perspective. Fig. 3 is a full-size sectional elevation of a part of my device; Fig. 4, a plan in which parts not shown in Fig. 1 are uncovered; Fig. 5, a partial section of a detail. Fig. 6 shows an alternative construction of Fig. 4; Fig. 7, a sectional elevation of a detail taken from a point at right angles to Fig. 3. Fig. 8 is a plan corresponding to Fig. 7.

In the drawings, A is the shell which encloses and supports the burner. It corresponds in shape with the boiler or other object to be heated and should be of sufficient height to inclose a burning-chamber and protect it from side drafts. When the object to be heated is a vertical steam-boiler, the shell A is preferably fitted and attached to it. The lower edge of A is bent upward, as shown in Fig. 2, to form a supporting-flange A', on which the ends of the perforated chambers N rest. These perforated chambers N serve both as burners and mixing-chambers. They are entirely similar in construction, and I prefer to make them by cutting drawn-steel tubing into proper lengths and plugging the ends. Each of the chambers N is divided into an upper and a lower part by the roof-shaped distributing-plate R, (shown in Figs. 4 and 6,) which is made to fit spring-tight in N and is perforated at the ridge by a series of holes o, that are spaced farther apart at the center than at the ends to help in equalizing the pressure of the mixed air and gas at the perforations w v in the upper surface of N. For a similar reason the two series of perforations w and v are equidistant from the series o. The perforated chambers N are placed parallel to each other and at equal distances apart. It is important that this separating-space between any two adjacent chambers N should be as narrow as will permit sufficient air to pass through, since any unnecessary flow of air wastes the heat from the burner and any increase in the width of the separating-spaces will increase the flow of air and will also make the action of the burner more easily affected by changing air-currents. Furthermore, when this separating-space is made narrow the cross-section of the adjacent chambers N and N becomes important. With the circular cross-section shown the air from the whole under

surface of the tubes flows smoothly into the narrow spaces between them and then spreads smoothly over the whole upper surface without forming noticeable eddies. For this reason when the cross-section of the chambers N is approximately the same as shown they can be placed much more closely to each other than would be possible with an irregular or angular cross-section. On the other hand, the advantages of the rounded cross-section very rapidly decrease with an increase in the width of the separating-spaces between N and N of Fig. 7.

Each of the tubes N fits into a seat milled for it in the upper side of the primary mixing-chamber M and is clamped thereto by a screw S, which passes through a counterbored hole h in the lower side of M. Although separate holes may be bored through N to admit the air and vapor from M, I prefer to make a chamber b in the upper part of S and connect it with M by one or more holes, as c, as shown in Fig. 5.

The primary mixing-chamber M is conveniently made, as shown, of a suitable piece of tubing plugged at the ends, and the cross-section shown has the further advantage that it does not noticeably obstruct the flow of air to the burning-apertures w v directly above it, since the air readily closes in over its rounded upper surface with little tendency to form eddies. The chamber M is preferably placed so as to cross the chambers N at right angles and divide each of them into two equal parts. In Figs. 2 and 4 the chamber M is shown as divided into two parts m m' by the partition P. These parts m m' are provided with the distributing-tubes D' D², to which feed-tubes K' K² are joined, that are fed with a mixture of air and vapor by blast-nozzles of the usual construction. The outer end of K' is turned at right angles to K², so that a gust of wind which is liable to blow out one half the burner will be little likely to affect the other. When this wind danger is considered unimportant, the mixing-chamber M may be left undivided, as in Fig. 6, and the single feed-tube K inserted at its middle point, where it enters the single distributing-tube D. The distributing-tubes D D' D² are placed close to the sides of M M', through which K K' K² enter, and are each perforated by a series of holes, as a, which open toward the adjacent sides of M or M'. These holes a are placed twice as far apart at the centers of D, D', or D² as at the ends in order to equalize the pressure in M or M'.

As hereinbefore stated, it is very important in the working of a burner for a steam-autobile that the vapor and air shall be as thoroughly mixed as possible with nearly sufficient air for its combustion. I have therefore provided for remixing, as above specified, the mixed air and vapor from a primary mixing-chamber close to the point of burning. If the mixing is carried to an extreme point in both the primary and secondary mixing-

chambers, it may produce an objectionable and needless back pressure. In such a case fairly good results may be obtained by throwing the larger part of the work on either the primary or the secondary chambers; but my experiments have led me to prefer to provide for the greater part of the mixing in the secondary chambers by the construction shown and described.

When I wish to make use of my invention, I blow gasolene-vapor into the outer ends of the tubes K K' in the usual manner, from which it passes into the distributing-tubes D D. Issuing from the perforations a in jets and striking the inner wall of M the air and vapor are mixed in a greater or less degree and pass upward through the perforated screws S into the chambers N, where after a more intimate mixture by issuing in jets from the holes o in the ridge of R and striking against the adjacent surface of N the combination of air and vapor issues from the series of apertures w and v and is lighted. The size of the flames is varied in the usual manner by varying the flow of gasolene. The evenness of pressure obtained by my construction and the smoothness of air-flow permit of running a very low flame when desired.

When, as shown in Figs. 2 and 4, two feed-tubes K K', acting at right angles, are used, it becomes nearly impossible for a gust of wind to blow out both sides of the burner at once, and the side blown out will immediately relight itself from the other flame. Even when but one feed-tube K' is used the combined action of various features hereinbefore specified greatly reduce the liability to flickering and blowing out, and any flame which is driven back into N by a gust of wind is chilled and smothered between N and R before it has time to do damage, and if by accident one of the chambers N is injured by heat it is easily removed, by turning out the screw S, and another put in its place.

Having now fully described my invention and the manner of using, what I claim, and desire to secure by Letters Patent, is—

1. In a gasolene-burner for steam-boilers, a supporting-shell which corresponds in shape with the boiler and has an inwardly-projecting flange that supports the other parts of the device, a series of parallel chambers perforated throughout their length to act as burners, separated by relatively narrow air-spaces, and approximately covering the whole lower opening of the shell and a mixing-chamber which is clamped to the lower side of each perforated chamber and communicates therewith; all in combination with each other and with means for supplying air and vapor to the mixing-chamber, substantially as and for the purpose set forth.

2. In a gasolene-burner for steam-boilers, a supporting-shell which corresponds in shape with the boiler and has an inwardly-projecting flange that supports the other parts of the burner, a series of parallel-sided chambers

resting upon the supporting-shell which have burner - perforations regularly distributed throughout their whole length, and vary in length to correspond with the varying width 5 of the supporting-shell, a mixing-chamber to which each parallel perforated chamber is attached near the middle of its lower side, and with which each communicates and a feed-tube through which air and vapor are supplied to the mixing-chamber, all combined with each other as and for the purpose set forth.

3. In a gasolene-burner a series of cylindrical chambers perforated on their upper 15 sides, a mixing-chamber having a series of transverse notches in its upper surface in which the cylindrical perforated chambers fit closely, and through which they communicate with the mixing - chamber, and a series of 20 screws which screw into the lower side of each perforated chamber, pass through the lower side of the mixing-chamber and clamp the perforated chambers to the mixing-chamber, all combined with each other and with means 25 of supplying air and vapor to the mixing-chamber, substantially as and for the purpose set forth.

4. In a gasolene-burner a series of cylindrical chambers perforated on the upper side, 30 a primary mixing-chamber having a curved upper surface, a series of transverse notches in this curved upper surface in which the perforated cylinders fit and through which they communicate with the primary mixing-cylinder, and a series of screws which, passing 35 through the lower side of the mixing-chamber and into the bottoms of the perforated cham-

bers clamp the perforated chambers to the primary mixing-chamber, all combined with each other and with means of supplying air 40 and vapor to the primary mixing-chamber substantially as and for the purpose set forth.

5. In a gasolene-burner, a series of perforated burner - chambers, a primary mixing-chamber, means of supplying air and vapor 45 thereto a series of screws which clamp the perforated chambers to the primary mixing-chamber and an air-chamber in each screw which communicates with both the primary mixing-chamber and the perforated chamber 50 all combined with each other as and for the purpose set forth.

6. In a gasolene-burner a cylindrical chamber closed at the ends, burning-apertures symmetrically arranged on the upper surface of 55 the chamber, a roof-shaped distributing-partition which fits tightly in the cylindrical chamber and divides it into an upper and a lower compartment, a series of perforations which pass through the upper part of the roof- 60 shaped partition and connect the upper compartment of the cylindrical chamber with the lower, and a connection between the lower side of the cylindrical chamber and a source of mixed air and vapor all as and for the purpose set forth.

In testimony whereof I have signed my name to this specification in the presence of two subscribing witnesses.
